(57) **CLAIM**

The ornamental design for a modular pallet, as shown and described.

DESCRIPTION

FIG. 1 is a top isometric view of a modular pallet showing the new design;

FIG. 2 is a bottom isometric view thereof;

FIG. 3 is a top plan view thereof;

FIG. 4 is a bottom plan view thereof;

FIG. 5 is a first side elevational view thereof;

FIG. 6 is a second side elevational view thereof;

FIG. 7 is a first end elevational view thereof;

FIG. 8 is a second end elevational view thereof;

FIG. 9 is a top isometric view of a modular pallet showing a second embodiment of the new design;

FIG. 10 is a bottom isometric view thereof;

FIG. 11 is a top plan view thereof;

FIG. 12 is a bottom plan view thereof;

FIG. 13 is a first side elevational view thereof;

FIG. 14 is a second side elevational view thereof;

FIG. 15 is a first end elevational view thereof; and,

FIG. 16 is a second end elevational view thereof.

The broken lines composed of short dashes form no part of the claimed design. The inventive aspects of the current embodiments exist in the modular pallet as a whole, in individual portions and/or elements thereof, and in combinations of portions and elements thereof. Applicant reserves the right to amend this application and/or to file one or more continuing applications to specifically claim any such arrangement or any specific embodiment or embodiments, including changing solid lines to broken lines to denote unclaimed subject matter by amendment or in a continuing application.
